Primary Examiner — John Windmuller*Assistant Examiner* — John R Yeh(74) *Attorney, Agent, or Firm* — Oblon, McClelland, Maier & Neustadt, L.L.P.(57) **CLAIM**

The ornamental design for a broom, as shown and described.

DESCRIPTION

FIG. 1 is a front, top, and right side perspective view of a broom;

FIG. 2 is a rear elevational view thereof;

FIG. 3 is a top plan view thereof; and,

FIG. 4 is a left side elevational view thereof, the right side elevational view being a mirror image of the left side elevational view shown.

The broken lines in the drawings illustrate environmental subject matter and form no part of the claimed design.

1 Claim, 4 Drawing Sheets(56)
